(57) **CLAIM**

The ornamental design for an LED headlight, as shown and described.

DESCRIPTION

FIG. 1 is a perspective view of a driver side LED headlight, showing our new design;

FIG. 2 is a front view of driver side LED headlight, the passenger side being a mirror image thereof; and

FIG. 3 is a side view of driver side LED headlight, the passenger side being a mirror image thereof;

FIG. 4 is a side view of driver side LED headlight, thereof, opposite that shown in FIG. 4;

FIG. 5 is a top plan view of driver side LED headlight, the passenger side being a mirror image thereof; and,

FIG. 6 is a bottom plan view of driver side LED headlight, the passenger side being a mirror image thereof.

Portions of the drawings shown in broken lines are for illustrative purposes only and form no part of the claimed design. The surface shading lines illustrate contour only and form no part of the present design.
